UNITED STATES PATENT OFFICE.

O. CHESTER COGGINS, OF NEW HAVEN, CONNECTICUT.

SHIFTING RAIL.

SPECIFICATION forming part of Letters Patent No. 274,174, dated March 20, 1883.

Application filed April 21, 1882. (No model.)

To all whom it may concern:

Be it known that I, O. CHESTER COGGINS, a citizen of the United States, residing at New Haven, in the county of New Haven and State 5 of Connecticut, have invented certain new and useful Improvements in Shifting Carriage-Seat Rails, of which the following is a specification, reference being had therein to the accompanying drawings, in which—

10 Figure 1 is a view of a carriage-seat and of the rail. Fig. 2 is an enlarged view of the back rail and of the knobs for holding the back quarters of the top and also the back curtain. Fig. 3 is a vertical and longitudinal section of 15 the back rail.

My improvement relates to carriage-seat rails, its object being to make a rail that is easily adjustable to seats of different lengths, and a rail to which the top may be fastened 20 in such a manner as to be removable with the rail from the seat.

To this end the improvement consists in the construction and arrangement of parts, as hereinafter more fully set forth.

25 To enable others to make and use my improved rail, I will describe it in detail.

A is the seat, to which the adjustable rail is fastened by screws or other suitable means. The similar side rails, B and C, have the parts 30 a and b, to which the top is attached, and also the parts indicated by the letter c, for fastening them to the seat. Their back ends are bent at right angles and enter the tube D, and are held in the tube by the set-screws e. The 35 tube D has the knobs o, to which the "back quarters," as the back pieces on the sides of the curtain are called, are fastened, so that the top is removable with the rail. As ordinarily constructed, the back quarters are attached to the seat and have to be disconnected 40 on the removal of the top. By making the back rail long enough and by attaching the back quarters to it by suitable means, the

top is in no way disturbed or wrinkled by the adjustment of the side rails. The set-screws e 45 may be threaded in the tube, or they may be threaded in the side rails, and slots may be made in the tube to allow the movement of the side rails for adjustment.

The construction may be somewhat varied 50 without departing from the spirit of my invention. For example, the back rail, D, may be a longitudinal section of a tube, except near its ends, where it is a tube; or it may be a flat bar of iron with tubular ends. 55

I am well aware that various devices have been employed to make carriage-seat rails adjustable to seats of different lengths.

I am also aware that carriage-seat rails have been made with tubular angle-couplings for 60 uniting the side and back rails; that side rails have been rabbeted to wood backs, and that side rails have been attached to back rails of different lengths, the adjustment to seats of 65 different lengths being made by a change of the back rail; but

What I claim as my invention, and desire to secure by Letters Patent, is—

A shifting rail for carriage-seats, composed of the side rails, B C, and the tubular back rail, 70 D, the side rails having their rear ends bent inward at a right angle to enter the ends of the tubular rail, and being held adjustably therein by means of set-screws e e, and the back rail being provided with means for securing 75 the back quarters and back curtain of the carriage-top, whereby they are removable together and the rails capable of adjustment without disturbing said back quarters, substantially as shown and described. 80

In testimony whereof I affix my signature in presence of two witnesses.

O. CHESTER COGGINS.
